UNITED STATES PATENT OFFICE

LESLIE DANA, OF ST. LOUIS, MISSOURI, ASSIGNOR TO CHARTER OAK STOVE & RANGE COMPANY, A CORPORATION OF MISSOURI

STOVE LEG

Application filed March 21, 1929. Serial No. 348,949.

This invention pertains to supporting legs, particularly adapted for stove bases and the like.

One object of this invention is the provision of readily attachable means for preventing the accumulation of dirt at the lower portion of a channeled leg member.

Another object of this invention is the simplification of such means, and the provision of means for maintaining the stove leg and protecting member flush with a level floor to prevent the collection of dirt at the lower portion of the channel of the leg.

Other objects and advantages of this invention will be apparent from the following detailed description of a preferred form of the invention.

In the accompanying drawings, in which like reference numerals refer to like parts—

Fig. 1 is an elevation, partly in section, of a stove leg embodying the invention, taken perpendicular to the flat face of the filler member;

Fig. 2 is a perspective view of the several parts entering into the construction, showing the relative positioning of the same in assembly; and

Fig. 3 is a sectional plan view taken on line 3—3 of Fig. 1.

Referring to the drawings, the construction therein illustrated comprises a channeled stove leg 10 formed with a foot portion 11 at its lower end, and also having means at its upper end for the rigid attachment of skirt members for rigidly holding the stove legs in proper position as hereinafter more fully described.

Ordinarily channeled leg constructions are subject to the disadvantages that dirt which collects behind the foot, in the channel, can be removed only with considerable difficulty and inconvenience. It has been proposed to form the foot portion of the leg as a solidly cast block, thus forming a solid filler member to prevent the accumulation of dirt. Such proposed construction is not practical, however, for several reasons, among which is the increased weight, the difficulty attending the formation in the same casting of a solid block

and a thin channeled member, and the unnecessarily large quantity of metal consumed.

According to this invention the leg member 10 is provided with a threaded boss 12 and with an upper lug 13 and lower lugs 14 to provide for the fixation of a filler member 15 in the channel at its foot portion. This filler member comprises a channel covering portion 16, formed to fit the open side of channeled leg 10 and extends upwardly from the foot portion thereof, and a tongue portion 17 is formed to extend into the channel and substantially fit the walls thereof, to prevent the upper end of channel covering portion 16 from entering too deeply into the channel and to prevent dust accumulation in the foot portion of the leg. This tongue portion 17 is preferably inclined upwardly as shown, so that dust and dirt will not tend to deposit thereon, and so that such dust as does cling thereto may be easily removed.

As shown most clearly in Fig. 1, the extremity of the tongue portion 17 engages with the lug 13 to prevent upward longitudinal movement of the filler member when placed in position.

Lugs 14 provide stops, to prevent the lower end of the channel covering portion 16 of the filler member 15 from entering too deeply into the channel, and also to contact with the lugs 18 formed on the channel covering portion 16, as shown, to prevent downward longitudinal movement of the filler member in the channel.

As shown in the drawings the filler member 15 is so proportioned that when engaged as above described with the lugs 13 and 14, the lower edge of the channel covering portion 16 lies in the same plane with the edge of the foot portion 11, so that when stood on a level surface the foot portion of the leg and the lower edge of the filler member fit flush against the surface.

The filler member is provided with a perforation 19 which may be reinforced with a boss as shown. This perforation is so placed as to be aligned with the boss 12 when the filler member is positioned in the channel. A machine screw 20 passed through the perforation and threadedly engaged with the boss

12 serves to securely fasten the filler member in position. The filler member is preferably removably attached to the leg so that it may be detached therefrom to be more readily cleaned should it become excessively soiled from long inattention.

It is preferable in order to prevent the accumulation of dirt around the stove leg, that the leg be so held that the foot portion and 10 the lower portion of the filler member will fit flush upon a horizontal surface, as the floor. To obtain this result I have provided means for assembling a plurality of legs into a base so that the several legs will be rigidly held 15 with the edges of their foot portions lying in substantially the same plane.

This means comprises skirt portions 21 having their end portions formed to abut the lateral portions 22 of the upper end of the 20 stove leg 10. The skirt portions are also provided with means for fastening them to the stove legs in this abutting relation, which may take the form of offset tongues 23 adapted to overlap the upper lateral portions of 25 said leg and to be fastened to the leg by machine screws passing through the tongues 23 and screwing into threaded bosses 24 formed in proper position on the inside of the upper portions of said legs 10.

30 By means of this construction a plurality of legs (usually 4) may be assembled with an equal number of skirt sections, and, by reason of the predetermined abutments between the skirts 21 and the edges 22, and the rigid fastening together of the members by means of tongues 23 and bosses 24, the several leg members 10 will be rigidly held at just the proper angle so that the lower edges of the foot portions and their filler members will all lie in 40 the same plane to fit flush on a level surface to prevent accumulation of dirt underneath the foot portions.

The base assembly composed of the legs and skirt members, may be used to support the 45 stove body, or the like in any desired manner. As the structure herein described is particularly adapted to be enameled, due to the smooth curves thereof, it is preferable that danger of damaging the enamel be minimized 50 by the provision of body supports 25, formed on the inside of the channeled leg, as shown, to carry the body portion 26 with its edge slightly spaced from the edges of the enameled legs and skirts, as indicated at 27, Fig. 1.

55 Obviously changes in detail and design may be made without departing from this invention, and I do not desire to be limited to the illustrative embodiment shown and described in detail, but define my invention in the following claims.

I claim:

1. In combination with a channeled leg member having a filler member at the foot thereof, and adapted to stand flush upon a 65 level surface when properly supported to

stand thereon, means for holding the leg in such position that the end of the leg and the filler member will fit flush with the surface, comprising edges formed at the upper lateral portions of said leg, skirt plates having portions formed to engage said edges and having offset tongues overlapping said upper lateral portions of said leg, and means for firmly attaching said tongues to said leg, whereby the assembly of a plurality of the legs and skirt members will maintain the foot portions and filler members in flush engagement with the level surface.

2. In combination with a channeled leg member having a filler member at the foot thereof, and adapted to stand flush upon a level surface when properly supported to stand thereon, means for holding the leg in such position that the end of the leg and the end of the filler member will fit flush with the surface, comprising edges formed at the upper lateral portions of said leg, skirt plates having portions formed to engage said edges and provided with means wherewith to be firmly fastened to said leg in said engaging position whereby the assembly of a plurality of the legs and skirt members will maintain the foot portions and filler members in flush engagement with the level surface.

3. In combination, a channeled leg, means removably positioned at the foot portion of the channel to prevent accumulation of dust at the foot portion thereof, and means for positioning the legs so that the foot portion of the leg and the removable means will fit flush against the floor.

4. In combination a channeled leg member adapted to stand upon a surface, a filler member fitting into said channel at the foot portion thereof and comprising a channel covering portion extending along the open side of said channel to close the same and adapted to abut said surface with its lower edge and a tongue portion extending into the channel at such an angle as to be normally inclined upwardly with respect to a horizontal plane when attached to said leg standing on said surface, said tongue being formed to substantially fit the wall of said channel, said channel being provided with means abutting said tongue portion for preventing longitudinal displacement of said filler member in one direction, means carried by said channel and abutting said channel covering portion to hold the same in channel covering position, means formed on said channel covering portion coacting with said last named means to prevent longitudinal movement of said filler member in the other direction, and means for fastening said filler member in position.

5. In combination, a channeled leg member adapted to stand upon a surface, a filler member fitting over said channel, said filler member comprising a portion extending along the

open side of said channel and adapted to abut the surface with its lower edge and a portion extending into said channel and fitting the walls thereof, said channel and filler member being provided with means to hold the two parts in relative position, and means for fastening the filler member to the leg, in such relative position.

5. In combination, a channeled leg member adapted to stand upon a surface, a filler member fitting over said channel and having its lower edge formed to stand upon said surface, interengaging means carried by said leg and filler member for holding the two parts in relative position, and means for fastening the filler member to the leg.

10. In combination, a channeled cast leg member provided with a boss and a plurality of lugs, a filler member, means for attaching said filler member to said boss, and means carried by said filler member and engaging said lugs for retaining said filler member in position.

15. In testimony whereof, I have signed my name to this specification.
